F. A. KELL,

CAR MOVER.

APPLICATION FILED SEPT. 29, 1920.

1,401,411.

Patented Dec. 27, 1921.

UNITED STATES PATENT OFFICE.

FRANK A. KELL, OF ST. LOUIS, MISSOURI, ASSIGNOR OF ONE-FOURTH TO W. C. DAVISON, OF ST. LOUIS, MISSOURI.

CAR-MOVER.

1,401,411.

Specification of Letters Patent. Patented Dec. 27, 1921.

Application filed September 29, 1920. Serial No. 413,561.

To all whom it may concern:

Be it known that I, FRANK A. KELL, a citizen of the United States, residing in the city of St. Louis, State of Missouri, have 5 invented a certain new and useful Improvement in Car-Movers, of which the following is a specification, reference being had to the accompanying drawing, forming a part thereof.

10 This invention relates generally to railway appliances and, more particularly, to a certain new and useful improvement in car-movers, the chief objects of my present invention being to provide a car-mover which 15 is adapted to seat upon the rail and which comprises actuatable members for gripping the wheel and imparting a turning or rotary movement thereto, to provide a car-mover which is relatively simple in construction, inexpensive of manufacture, convenient in use, adapted for selective location upon either rail, and efficient in operation, and to improve upon and simplify the construction of car-movers generally.

20 With the above and other objects in view, my invention resides in the novel features of form, construction, arrangement, and combination of parts hereinafter described and afterward pointed out in the claims.

25 In the accompanying drawing,

Figure 1 is a side elevational view of a car-mover embodying my invention, the same being shown operatively arranged upon a rail and in connection with a car-

30 wheel to be moved;

Fig. 2 is a plan view of the car-mover;

Fig. 3 is a rear elevational view of the car-mover seated upon a rail shown in section; and

35 Figs. 4 and 5 are detail transverse sectional views taken on the lines 4-4 and 5-5, respectively, of Fig. 2.

Referring now more in detail to the said drawing, in which like reference characters 40 indicate like parts throughout the several views, my new car-mover comprises a base 1 preferably in the form of a suitably elongated rectangular oblong plate of suitable width to conveniently seat upon the standard rail R, base-plate 1 being preferably provided at and along its opposite side margins with downwardly presented flanges 2-2 adapted to prevent sidewise slipping of the car-mover when seated upon the rail.

45 Integral with, or otherwise rigidly fixed to,

and rising from, the base-plate 1, are suitably spaced standards 3-3.

Supported at its ends by the standards 3, is a pintle 4, and hingedly or pivotally mounted intermediate their length upon the 50 pintle 4 for swinging movement between and relatively to the standards 3, is a pair of spaced suitably elongated members or, as I shall call them, fingers 5-5, which are cut away adjacent their forward ends and upon 55 their inner faces and thereby provided or formed with oppositely inclined or obliquely disposed cam-surfaces 6-6, for purposes shortly appearing, the inner faces of the fingers 5 to the rear of the cam-surfaces 6 being preferably straight, as seen in Fig. 4.

The fingers 5-5 are provided or formed at their forward ends with bifurcated or forked extensions 7-7, which project forwardly beyond the cam-faces 6, as seen in Fig. 2. Supported at its end by the extensions 7, is a second pintle 8, and hingedly or pivotally mounted upon the pintle 8 for 60 swinging movement intermediate the finger-extensions 7, is a shoe 9 having a working or wheel-engaging face 10 lengthwise arcuated to conform to the curvature of the standard car-wheel W. The shoe 9 is provided upon each side with a pair of outwardly projecting lateral pins 11, which are 65 adapted to freely extend through suitable apertures provided transversely in so-called auxiliary shoes 12-12 also hingedly or pivotally mounted upon the pintle 8 for swinging movement in the bifurcations of the respective finger-extensions 7 and each also provided with a working-face 13 preferably arcuated to similarly conform to the 70 curvature of the car-wheel W, the pins 11, while freely permitting movement of the auxiliary shoes 12 laterally away from or toward the central or main shoe 9, maintaining the auxiliary shoes 12 and main shoe 9 in proper operative or wheel-gripping relation.

By so arranging or duplicating the auxiliary shoes 12 upon each side of the main or central shoe 9, it will be evident that the car-mover may be selectively located and operatively employed upon each rail of a standard track, one or the other of the shoes 12, as the car-mover may be located either on the right or left rail, being adapted to coöperate with the main shoe 9 in gripping the flange of the wheel W; and 75 80 85 90 95 100 105 110

for facilitating gripping engagement between either of the shoes 12 and the shoe 9 with the wheel W, the inner margin of each working-face 13 and both margins of the 5 working-face 10 are preferably beveled, as best seen in Fig. 2.

Interposed between, and preferably of somewhat greater dimension vertically than, the fingers 5—5, and also hingedly or pivotally 10 mounted intermediate its length upon the pintle 4, as best seen in Figs. 2 and 4, is a cam-member 14 forming part of a suitably elongated rearwardly projecting operating lever 15, the cam-portion 14 having its 15 side faces suitably cut away or inclined, as at 16—16, for engaging the inner faces of the fingers 5—5, for purposes shortly appearing. At its forward end, the cam-portion 14 of the lever 15 is provided with an 20 extension 17 formed at its sides with oppositely disposed oblique or cam-faces 18—18 for coöperation with the cam-faces 6—6 of the fingers 5.

In use or operation, the car-mover is seated upon either right or left rail, as may 25 selectively be desired, and slidably moved thereupon to project shoe 9 into engagement with the tread face of the wheel W to be moved, or into what I may describe as normal operating position. As so located, and assuming that the car-mover has been seated on the right rail R, the flange W' of the wheel will fit or project into the space provided between the main shoe 9 and the left-hand auxiliary shoe 12. Should it be found necessary in so operatively positioning the car-mover to increase the space between the 30 shoes 9 and 12 in order that the wheel-flange may be firmly gripped, the lever-handle 15 is swung upwardly, whereupon lever-extension 17 is moved downwardly, whereby, through the cam-engagement between the coöperating faces 18 and 6, the finger-extensions 7 are forcibly spread apart and 35 the auxiliary shoe 12 moved laterally relatively to the main or central shoe 9. The flange W' of the wheel being so accommodated, downward pressure is now exerted upon the lever 15, whereupon spreading 40 force between the finger-extensions 7 is first removed, and then, as lever 15 is forced downwardly, the cam-portion 14 thereof engages at its cam-faces 16 with the fingers 5 and forces or spreads apart the major portions 45 of the fingers 5 lying to the rear of the pintle 4 and, at the same time, forces the finger-extensions 7 to move toward each other. In such movement of the finger-extensions 7, the particular auxiliary shoe 12 is correspondingly forced toward the main, or 50 relatively fixed, shoe 9 and the wheel-flange W' thereby firmly gripped by and between the auxiliary shoe 12 and the main shoe 9, and I may here state that, as seen in Fig. 2, 55 the beveled margins of the several shoes may

be corrugated or roughened to increase the gripping engagement between the shoes and the wheel. On downward pressure upon the lever 15 being continued, the finger-extensions 7 are swung upwardly on the 70 pivot 4, the several shoes 9 and 12, engaging both the tread-face of the wheel and the flange thereof, correspondingly swung upwardly, as seen in dotted lines in Fig. 1, and a turning movement upon its own axis imparted to the engaged or gripped wheel. Upon downward pressure upon lever 15 being then removed, spreading force upon the fingers 5 is released, the auxiliary shoe 12 moved laterally away from the 80 central shoe 9, and both the shoes 9 and 12 disengaged from the wheel, when the car-mover may be again actuated into so-called normal position relatively to the wheel W for imparting further rotary or turning 85 movement thereto as here described.

I am aware that changes in the form, construction, arrangement, and combination of the several parts of my new car-mover may be made and substituted for those herein 90 shown and described without departing from the nature and principle of my invention.

Having thus described my invention, what I claim and desire to secure by Letters 95 Patent is:

1. A car-mover including, in combination, a base adapted to seat upon a rail, an operating lever mounted for swinging movement upon and relatively to the base, 100 and a plurality of members pivotally carried by the lever for engagement with the car-wheel and its flange, one of said members being adapted for engagement upon the tread-face of the wheel.

2. A car-mover including, in combination, a base adapted to seat upon a rail, an operating lever mounted for swinging movement upon and relatively to the base, and a plurality of shoes pivotally carried by the lever 110 for engagement with the car-wheel and its flange, one of the shoes being adapted for engagement upon, and arcuated to conform to, the tread-face of the wheel.

3. A car-mover comprising, in combination, a base adapted to seat upon a rail, a pair of wheel-engaging members, and means mounted on the base and having connection with the wheel-engaging members for actuating the same to engage the wheel and its 115 flange for imparting a turning movement thereto, one of the wheel-engaging members being adapted for engagement upon the tread-face of the wheel.

4. A car-mover comprising, in combination, a base adapted to seat upon a rail, a pair of fingers mounted for movement upon and relatively to the base, wheel-engaging members swingably carried by the fingers, and means for actuating the fingers to cause 125

the wheel-engaging members to engage the wheel and its flange for imparting a turning movement thereto, one of the wheel-engaging members being adapted for engagement upon the tread-face of the wheel.

- 5 5. A car-mover comprising, in combination, a base adapted to seat upon a rail, a pair of fingers hinged upon the base, wheel-engaging shoes mounted for swinging movement upon the fingers, and a lever pivoted upon the base for actuating the fingers to cause the shoes to engage the wheel and its flange for imparting a turning movement thereto, one of the wheel-engaging members 65
10 being adapted for engagement upon the tread-face of the wheel.

- 10 6. A car-mover comprising, in combination, a base adapted to seat upon a rail, a pair of spaced fingers hinged upon the base, 70 wheel-engaging shoes mounted for swinging movement on the fingers, and a lever pivoted upon the base and having a cam-portion disposed between the fingers for actuating the fingers both laterally and swingably to cause the shoes to grip the wheel and impart a turning movement thereto.

- 15 7. A car-mover comprising, in combination, a base adapted to seat upon a rail, a pair of spaced fingers hinged upon the base, 75 a plurality of wheel-engaging shoes mounted independently for swinging movement on the fingers, a lever pivoted upon the base and having a cam-portion disposed between the fingers for actuating the fingers both laterally and swingably to cause the shoes to grip the wheel and impart a turning movement thereto.

- 20 8. A car-mover comprising, in combination, a base adapted to seat upon a rail, a pair of spaced fingers hinged upon the base, a pair of wheel-engaging shoes mounted independently for swinging movement upon 80

- 25 the fingers, a lever pivoted upon the base and having a cam-portion disposed between the fingers for actuating the fingers both laterally and swingably to cause the shoes to grip the wheel and impart a turning movement thereto, and pins on one of the 85 shoes loosely engaging the other shoe for maintaining the shoes in operative relation throughout their movement.

- 30 9. A car-mover comprising, in combination, a base adapted to seat upon a rail, a pair of spaced fingers hinged upon the base, wheel-engaging shoes mounted for swinging movement upon the fingers, and a lever pivoted upon the base and having cam-portion 90

- 35 60 tions for actuating the fingers to cause the shoes to engage the wheel and its flange for

imparting a turning movement thereto and to then release the wheel, one of the wheel-engaging members being adapted for engagement upon the tread-face of the wheel. 65

10. A car-mover comprising, in combination, a base adapted to seat upon a rail, a pair of fingers hinged upon the base, a main wheel-engaging shoe mounted for swinging movement upon the fingers, auxiliary wheel-engaging shoes also mounted for swinging movement upon the fingers, the auxiliary shoes being disposed upon opposite sides of the main shoe, whereby the car-mover may be selectively located for operation upon 70 either rail, and a lever pivoted upon the base for actuating the fingers to cause one or the other of the auxiliary shoes to coöperate with the main shoe to grip the wheel and impart a turning movement thereto. 75

11. A car-mover comprising, in combination, a base adapted to seat upon a rail, a pair of fingers hinged upon the base, bifurcated extensions on the fingers, a main wheel-engaging shoe mounted for swinging movement upon and intermediate the extensions, an auxiliary wheel-engaging shoe mounted for swinging movement upon and intermediate the bifurcations of each extension, whereby the car-mover may be selectively located for operation upon either rail, and a lever pivoted upon the base for actuating the fingers to cause one or the other of the auxiliary shoes to coöperate with the main shoe to grip the wheel and impart a 95 turning movement thereto. 90

12. A car-mover comprising, in combination, a base adapted to seat upon a rail, a pair of spaced fingers hinged upon the base, bifurcated extensions on the fingers, a main wheel-engaging shoe mounted for swinging movement upon and intermediate the extensions, an auxiliary wheel-engaging shoe mounted for swinging movement upon and intermediate the bifurcations of each extension, whereby the car-mover may be selectively located for operation upon either rail, a lever pivoted upon the base and having a cam-portion disposed between the fingers for actuating the fingers to cause one or the other of the auxiliary shoes to coöperate with the main shoe to grip the wheel and impart a turning movement thereto, and an extension on the lever adapted for camwise engagement with the 100 fingers to actuate the finger-extensions to cause said main and auxiliary shoes to release the wheel. 105

In testimony whereof, I have signed my name to this specification.

FRANK A. KELL.
